A. B. SPERRY.
TELEPHONE SYSTEM.
APPLICATION FILED NOV. 8, 1919.

1,406,236.

Patented Feb. 14, 1922.

UNITED STATES PATENT OFFICE.

ARTHUR B. SPERRY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,406,236.

Specification of Letters Patent. Patented Feb. 14, 1922.

Application filed November 8, 1919. Serial No. 336,537.

To all whom it may concern:

Be it known that I, ARTHUR BRUCE SPERRY, a citizen of the United States, residing at New York, in the county of New York, State of New York, have invented certain new and useful Improvements in Telephone Systems, of which the following is a full, clear, concise, and exact description.

This invention relates to telephone systems and particularly to an alarm signaling apparatus within such systems.

It is the object of the invention to provide a slow acting device by means of which an alarm will be operated if an unstandard condition arises and continues for more than a predetermined interval of time.

The feature of this invention is a circuit equipped with a number of relays which act and react through a plurality of cycles to establish a circuit for the alarm signaling apparatus.

Heretofore slow acting devices, such as that shown in the Patent No. 1,279,811, granted September 24, 1918, to Williams, have been provided, but there the timing is dependent on the number of relays, each of which operates at a single time. In the present case the number of relays is reduced and a new method of timing is introduced through which certain relays act and react, that is, they go through several complete cycles of operation.

The drawing is a diagrammatic representation of a circuit employed in carrying out this invention. It represents a telephone line, a non-numerical switch and a numerical switch. Connecting into the circuit of the numerical switch is the circuit of the timing apparatus which will be operated if the numerical switch is not set within a predetermined time.

The operation of the timing device will first be described. Within the circuit of the numerical switch is a slow releasing relay O. Under certain conditions, this relay attracts its armatures to cause certain circuit changes which will hereinafter be more fully described. At the right-hand armature and front contact a circuit is made to ground, which is connected through the left-hand armature and back contact of the relay 3 to the winding of relay 1. Relay 1 attracts its armature and therethrough establishes a connection from ground at the armature of relay O to the winding of relay 2. Relay 2, in

turn, through its right-hand armature connects ground to the winding of relay 3, which thereupon attracts its armatures. At its left-hand armature and back contact relay 3 opens the circuit of relay 1, but relay 1, being slow to release, does not immediately retract its armatures. When it does, however, a circuit is established from ground at the armature of relay O to the normal contact of relay 1, the left-hand armature and front contact of relay 2, the winding of relay 4, to battery and ground. When relay 4 attracts its armature it brings relay 5 into the circuit, but relay 5 at this time is short circuited, due to the ground connected to the upper connection to its winding and also to ground connected to the armature and contact of relay 4. Relay 1 in retracting its armatures also opens the circuit of relay 2, but relay 2 being slow to release does not immediately retract its armatures. When it does, however, at its right-hand armature and front contact, it opens the circuit of relay 3 which retracts its armatures. At the left-hand armature and front contact of relay 2, the shunt is removed from around relay 5 and a circuit is now provided from ground, to right-hand armature and contact of relay O, the winding of relay 5, the armature and contact of relay 4, the winding of relay 4, to battery and ground. In this manner relay 4 remains energized and relay 5 becomes energized. Relay 5 at its left-hand armature and back contact opens the original energizing circuit of relay 4 and at its right-hand armature closes a substitute circuit for relay 3 which, however, is not effective at this time. Upon the retraction of its armatures (relay 3), the original circuit for relay 1 is again established and it attracts its armature, thereby again establishing the circuit for relay 2. Relay 2, in turn, through its right-hand armature establishes a circuit for relay 3, which attracts its armatures and closes the substitute circuit for itself, so that it is now locked up in a circuit from ground, contact and right-hand armature of relay O, the left-hand armature and front contact of relay 3, the contact and right-hand armature of relay 5, winding of relay 3, to battery and ground. Relay 3 as before opens the energizing circuit of relay 1. Relay 1 after an interval retracts its armatures and thereupon reopens the circuit of relay 2. Relay 2 also after an interval retracts its armatures and thereupon

the circuit for the signaling means 6 is closed. This circuit extends from ground, to contact and right-hand armature of relay 0, the normal contact of relay 1, the left-hand armature and back contact of relay 2, the contact and right-hand armature of relay 3, the signaling means 6, which may be in the form of a relay to close a master circuit, or it may be an ordinary vibrating electric bell, and thence to battery and ground.

In this manner then is the ground at the right-hand armature of relay 0 extended to the signaling means 6, after an interval which is determined by the time taken for 15 two complete cycles of operation of relays 1 and 2.

The application of this timing circuit is of established importance in a telephone system as shown. Suppose a subscriber at 20 station A removes his receiver from its hook to establish a call to some other telephone line. Immediately a switch represented by the brushes 7 will come into operation in a well known manner. These brushes are the 25 ordinary representation of what is known as a line finder switch. Thereupon the circuit of the substation A will be extended to the winding of relay 8 and current flows from battery, to left-hand winding of relay 8, the 30 inner lower armature and back contact of relay 9, apparatus at substation A, the upper armature and back contact of relay 9, and right-hand winding of relay 8, to ground. Relay 8 becomes energized in this circuit and 35 through its armature places a ground on relay 0 which attracts its armatures. If the subscriber now manipulates his impulse sending device 10, the armature of relay 8 will vibrate. Each deenergization of relay 40 8, in response to the impulses transmitted, establishes a circuit from ground, armature and back contact of relay 8, back contact and lowermost armature of relay 9, the inner left-hand armature and front contact of relay 0, the winding of relay 11, the winding 45 of primary magnet 12, to battery and ground. Magnet 12 responds to each separate impulse but relays 11 and 0 remain energized through the sending of the whole train.

Magnet 12 moves the brushes 13, 14 and 50 15 into association with a particular group of lines. At the end of the series of impulses, relay 11 becomes deenergized. During its energization ground is extended through 55 its front contact and armature to the winding of relay 16 and thence to battery and ground. Relay 16 attracts its left-hand armature and thereby locks up in a circuit from ground, the front contact and outer 60 left-hand armature of relay 0, the contact 17 of the off normal contact which is operated upon the first primary step of the switch, the right-hand armature and back contact of the secondary magnet 18, armature, front contact, and winding of relay 16,

to battery and ground. When relay 11 becomes deenergized the original ground for the energization of relay 16 is removed, but the ground which now holds relay 16 energized is connected through the armature and back contact of relay 11 to the back contact and left-hand armature of secondary magnet 18, winding of secondary magnet 18, to battery and ground, whereupon secondary magnet begins to operate automatically.

We will assume that the first trunk with which the brush 15 associates itself, is busy. This busy condition will be denoted by a ground on the terminal 19. As the secondary magnet 18 moves the brushes 13, 14 and 15 into association with this first trunk, and as it nears the end of its stroke, its armatures leave their contacts and open the respective circuits completed thereby. The ground for the energization of relay 16 is thereby removed, but since the first trunk has been assumed to be busy, the substitute ground will be connected from contact 19, brush 15, the armature and front contact of relay 16, the winding of relay 16, to battery and ground, to hold relay 16 energized. Upon the second step of magnet 18, an idle trunk is encountered and this is denoted by the absence of ground on terminal corresponding to 19. In this case no substitute ground for the relay 16 is found. Relay 16 deenergizes and at its armature and front contact opens the circuit for the energization of the secondary magnet 18. When the secondary magnet 18 comes to rest with its armatures in their retracted position, the ground which was heretofore provided for holding relay 16 energized is now connected through the right armature and contact of magnet 18 to the winding of relay 9. Relay 9 in attracting its armatures cuts the relay 8 off from the line and out of the control of the subscriber's substation A. Relay 9, also at its lowermost armature and contact, opens the circuit of the release magnet which was heretofore held open at the innermost armature and contact of relay 0.

Throughout this operation the operation of the timing device consisting of relays 1 to 5, inclusive, and the alarm signaling apparatus was going on, but in the ordinary case the operation would not be completed until some time after the brushes 13, 14, 15 were properly placed on the terminals of the idle line. Therefore, when relay 9 operates and relay 8 is removed from the control of the substation A, it retracts its armature and deenergizes the relay 0 which, in turn, removes the energizing ground from the timing arrangement. Therefore, the alarm signaling 125 6, will not be operated when the numerical switch is operated in the ordinary manner.

Or as sometimes happens the receiver at substation A is accidentally removed from its

hook, or if the line in any way becomes short circuited, switch 7 will act and in turn relays 8 and 0 will become energized and remain so for an indefinite period. If a predetermined length of time elapses as defined by the operations of relays 1 and 2 as described, the signaling device 6 will operate and an attendant will be notified thereby that an unstandard condition in a numerical switch has arisen whereupon he may take the necessary measures to remedy this condition.

What is claimed is:

1. In a telephone system, a timing device consisting of an organization of circuits and relays, said relays being arranged in said circuits to act and react through a plurality of cycles to render said device effective.
2. In a telephone exchange, a circuit to be supervised, a plurality of relays associated with said circuit and initially energized and deenergized in succession when said circuit is closed, means for again causing the same cycle of operations if the same circuit remains closed for a predetermined period, and a signal operated only upon the completion of the second cycle of operations.
3. In a telephone system having therein a timing device comprising an organization of circuits, relays and a signaling device, a plurality of relays responsive to the actuation of said timing device by one complete cycle of operations consisting of one energization and one deenergization each to prepare a circuit for said signaling device, and responsive to the continued actuation of said timing device by a second complete cycle of operations to render effective said circuit for said signaling device.
4. In a telephone system, a timing device consisting of an incoming line, a plurality of relays, an outgoing line and an alarm signal device, said relays being responsive to a prolonged change of potential on said incoming line to connect said incoming line

to said outgoing line and said alarm signal device being responsive to a change of potential on said outgoing line, said relays being included in a circuit arrangement whereby a first relay is energized by said change of potential on said incoming line, a second relay is energized in response to the energization of said first relay, a third relay is energized in response to the energization of said second relay, said first relay thereupon being deenergized in response to the energization of said third relay, a fourth relay being then energized in response to the deenergization of said first relay and the continued energization of said second relay, said second relay being thereupon deenergized in response to the deenergization of said first relay, said third relay being thereupon deenergized in response to the deenergization of said second relay, a fifth relay being thereupon energized in series with said fourth relay in response to the deenergization of said second relay, said first relay being thereupon energized in response to the deenergization of said third relay, said second relay being thereupon energized in response to the energization of said first relay, said third relay being thereupon energized in response to the energization of said second relay and being locked in response to the continued energization of said fifth relay, said first relay being thereupon deenergized in response to the energization of said third relay, said second relay being thereupon deenergized in response to the deenergization of said first relay and said incoming line being thereupon connected to said outgoing line in response to the coincident energization of said third relay and the deenergization of said first and second relays.

In witness whereof, I hereunto subscribe my name this 6th day of November A. D., 1919.

ARTHUR B. SPERRY.
